US0D1074683S

(12) **United States Design Patent** (10) **Patent No.:** **US D1,074,683 S**
(45) **Date of Patent:** **** May 13, 2025**

(54) **CONNECTOR ADAPTER FOR PORTABLE ELECTRONIC COMPUTING DEVICE**

(71) Applicant: **Pioneer Square Brands, Inc.**, High Point, NC (US)

(72) Inventor: **Riley Edvin Lynch**, Greensboro, NC (US)

(73) Assignee: **Pioneer Square Brands, Inc.**, High Point, NC (US)

(**) Term: **15 Years**

(21) Appl. No.: **29/980,810**

(22) Filed: **Dec. 27, 2024**

(51) **LOC (15) Cl.** **14-02**

(52) **U.S. Cl.**

USPC **D14/433; D13/108**

(57) **CLAIM**

The ornamental design for a connector adapter for portable electronic computing device as shown and described.

DESCRIPTION

FIG. 1 is a front perspective view of a connector adapter for portable electronic computing device showing my new design.

FIG. 2 is a front elevational view thereof.

FIG. 3 is a rear elevational view thereof.

FIG. 4 is a top plan view thereof.

FIG. 5 is a bottom plan view thereof.

FIG. 6 is a right elevational view thereof.

FIG. 7 is a left elevational view thereof; and,

FIG. 8 is a rear perspective view thereof.

The broken lines in the drawing figures depict portions of the connector adapter for portable electronic computing device that form no part of the claimed design.

1 Claim, 8 Drawing Sheets
